UNITED STATES PATENT OFFICE.

ROBERT SIEGFRIED, OF PITTSBURG, PENNSYLVANIA, ASSIGNOR TO WESTINGHOUSE ELECTRIC & MANUFACTURING COMPANY, A CORPORATION OF PENNSYLVANIA.

BRUSH-HOLDER.

956,739.

Specification of Letters Patent.

Patented May 3, 1910.

Application filed November 3, 1906. Serial No. 341,906.

To all whom it may concern:

Be it known that I, ROBERT SIEGFRIED, a citizen of the United States, and a resident of Pittsburg, in the county of Allegheny and 5 State of Pennsylvania, have invented a new and useful Improvement in Brush-Holders, of which the following is a specification.

My invention relates to brush holders for dynamo-electric machines and it has for its 10 object to provide a brush holder that shall be formed entirely from punched pieces of sheet metal and that shall be simpler in construction and cheaper to manufacture, while at the same time more satisfactory in service, 15 than others heretofore provided.

Figure 1 of the accompanying drawing is a plan view of a brush holder embodying my 20 invention, some of the parts of which have been removed for the sake of clearness of illustration. Fig. 2 is a view, in side elevation, of the brush holder of Fig. 1. Fig. 3 is a face view of one of the punched pieces 25 of sheet metal from which the brush holder is formed, and Fig. 4 is an edgewise view of the piece shown in Fig. 3.

The brush holder comprises two side by side punched pieces 1 and 2 of sheet metal that are secured together at convenient 30 places by means of rivets 3, the pieces being spread apart and bent near one end to form a rectangular box or guide 4 for a brush 4^a. The brush 4^a is provided with a conducting shunt 5, one end of which is secured, by means of a tap screw 6, to the extreme end 35 of the holder, or it may be secured thereto at any other desired and convenient place. The pieces 1 and 2 are provided, near the other end, with corresponding apertures, and with sleeves 7 that are formed around the 40 apertures by drifting or pressing to project outwardly therefrom. The brush holder is mounted upon a bar 8, the sleeves 7 forming a suitable bearing surface therefor. After the pieces are riveted together, they are 45 slotted at 9, by means of a saw or otherwise, from the apertures to the nearest end, and are spread apart and bent at this end to form an opening for the reception of a bolt 10, whereby the brush holder may be 50 securely clamped to the bar 8. The upper edges of the pieces 1 and 2 are provided with substantially circular projections 11 and 12, around the edge of the latter of which are formed hook-shaped stops 13 that are bent 55 at right angles to the plane of the piece.

The projections 11 and 12 are spread apart and provided with central bearings for a rod 15 which is surrounded by a spiral spring 14. The inner end of the spring 14 is fastened to the rod 15 and its outer end 60 is extended to form an arm which engages the outer end of the brush 4^a. An arm 16 is secured to one end of the rod 15 and co-operates with the stops 13 to effect adjustment of the pressure that may be exerted by the 65 spring 14 upon the brush 4^a.

The parts of the brush holder may assume other forms and may be otherwise arranged with reference to each other without departing from the invention, and I desire that all 70 such modifications shall be included within its scope.

I claim as my invention:

1. A brush holder for dynamo-electric machines comprising two side by side sheet 75 metal pieces riveted together in close engagement except at one end where they are spread apart and bent to form a box for the brush.

2. A brush holder for dynamo-electric 80 machines comprising two side by side sheet metal pieces riveted together in close engagement but spread apart at one place to form a box for the brush and at another place for the reception of means for exerting 85 pressure upon the brush.

3. A brush holder for dynamo-electric machines comprising two side by side sheet metal pieces riveted together in close engagement but spread apart and bent at one 90 end to form a box for the brush and provided with lateral projections near the other end between which is supported means for exerting pressure upon the brush.

4. A brush holder for dynamo-electric 95 machines comprising two side by side sheet metal pieces riveted together in close engagement but spread apart and bent at one end to form a box for the brush and provided with lateral projections between which 100 is supported a spring whereby pressure may be exerted upon the brush.

5. A brush holder for dynamo-electric machines comprising two side by side sheet metal pieces riveted together in close engagement but spread apart and bent at one 105 end to form a box for the brush and provided with projections between which is supported a spring, whereby pressure may be exerted upon the brush, and means for 110

adjusting the pressure that may be exerted upon the brush.

6. A brush holder for dynamo-electric machines comprising two side by side sheet metal pieces riveted together and bent apart at one end to form a box for the brush and having lateral projections at the other end, one of which is provided with stops, a spring located between the projections, and means adapted to coöperate with the stops for adjusting the spring.

7. A brush holder for dynamo-electric machines comprising two side by side sheet metal pieces having projections, one of which is provided with stops, a spring located between the projections, and means for coöoperating with the stops to adjust the spring, said pieces having apertures and surrounding lateral sleeve projections, and slotted ends that are spread apart and bent to receive a clamping device.

8. A brush holder for dynamo-electric machines comprising two side by side sheet metal pieces having projections, one of which is provided with stops, a spring located between the projections, and means for coöoperating with the stops to adjust the

spring, said pieces having apertures and surrounding lateral sleeve projections, and slotted ends that are spread apart and bent to receive a clamping device, the other ends of said pieces being also spread apart and bent to form a box for the brush.

9. A brush holder for a dynamo-electric machine comprising two side by side sheet metal pieces having apertures and surrounding lateral sleeve projections and slotted ends, said pieces being spread apart and bent to receive a clamping device.

10. A brush holder for dynamo-electric machines comprising two side by side sheet metal pieces having apertures and surrounding lateral sleeve projections and slotted ends, said pieces being spread apart and bent to receive a clamping device, and also spread apart and bent to form a box for the brush.

In testimony whereof, I have hereunto subscribed my name this 25th day of October, 1906.

ROBERT SIEGFRIED.
